(57) **CLAIM**

The ornamental design for a portable electrical energy storage device with components, as shown and described.

DESCRIPTION

FIG. 1 is a front perspective view of a portable electrical energy storage device with components showing our new design, a rear perspective view being a mirror image thereof.

FIG. 2 is a perspective view of the bottom thereof.

FIG. 3 is a top plan view thereof.

FIG. 4 is a bottom plan view thereof.

FIG. 5 is a right side elevational view thereof.

FIG. 6 is a left side elevational view thereof.

FIG. 7 is a front elevational view thereof; and,

FIG. 8 is a rear elevational view thereof.

Stippling and contour lines shown in FIGS. 1-8 are intended to represent approximate three-dimensional contours of the design, and are not intended to indicate surface decoration. The broken lines in FIGS. 2 and 4 are for the purpose of illustrating environmental structure and form no part of the claimed design.
